(57) **CLAIM**

The ornamental design for a cup holder, as shown and
described.

DESCRIPTION

FIG. 1 is a perspective view of a cup holder showing my new
design;

FIG. 2 is a front elevational view thereof;

FIG. 3 is a rear elevational view thereof;

FIG. 4 is a left side view thereof;

FIG. 5 is a right side view thereof;

FIG. 6 is a top plain view thereof;

FIG. 7 is a bottom plain view thereof; and,

FIG. 8 is a perspective view of an embodiment of the cup
holder being connected to a car ventilator grill.

The broken lines are for illustrative purposes only and form
no part of the claimed design.
